ENGLAND

METAL SPOOL

Application filed August 2, 1929, Serial No. 382,999, and in Great Britain August 10, 1928.

This invention relates to metallic spools, for camera film rolls and the like, and particularly to the manufacture of the spindles therefor.

6 The object of the invention is to facilitate the production of suitable metallic spindles which will be of low weight, cheap to manufacture, and sufficiently strong for the purposes to which they are to be put.

10 The class of spindle to which the invention relates is that in which a spindle is formed from a flat substantially rectangular strip which is bent or rolled up into a hollow cylinder with opposite edges of the strip lying adjacent to one another, the diameter of the cylinder being governed by the original width of the strip. Opposite edges of the strip are turned in to form a guiding passage on each side of the internal longitudinal slot left between the adjacent, opposite edges. The term "internal" is here used to indicate that the slot does not extend up to either of the ends of the spindle. According to the present invention, the inturned edges extend 25 axially beyond the ends of the internal slot, though not up to the very ends of the spindle.

In a process for making such a metallic spindle, according to the present invention, the four corners of a rectangular strip are 20 removed, as by punching and opposite longitudinal edges of the strip between the removed corners are bent off about parallel inset lines which do not extend as far as the removed corners to form, with the main flat 25 part of the strip, a shallow channel; and the flat portion of the strip is then bent or rolled up to form a hollow cylinder with the opposite or bent-off edges extending into the interior thereof. By arranging for the bent-off edges to be bent about parallel lines which are inset slightly from the edges of the flat portion of the strip an internal slot will be left in the spindle between the bent-off edges. The hollow cylinder thus formed is then set (i. e., strained so as not to un-roll) by having its ends splayed outwardly, or it may be held set by fixing its ends to the end discs in an appropriate manner.

Moreover, the length of the bent-off edges, 50 which is greater than the length of the slot

left therebetween when the spindle is formed, may be so chosen that the appropriate adjacent end of the bent-off edges can form a bottom rest for the camera key when it enters the cooperating slot in the appropriate end disc of the spindle.

The bent-off edges act to strengthen the spindle, thus allowing a very thin metallic strip of material to be used and a perfectly rigid spindle (for the use to which it is intended to be subjected) to be formed. A satisfactory spindle can be built in this manner the weight of which is less than the weight of a similar-sized spindle formed of wood. The rounding off of the edges of the slot, due to the material being bent thereat, provide a useful guide for the end of the paper or like roll, the full advantage of which will be appreciated when the film roll is being wound on the spindle in a dark room. 70 A manufacturing point in this construction is that the bent-off edges prevent overlapping when the flat portion of the strip is bent or rolled up to form the hollow cylinder.

One arrangement according to the invention will now be fully described with reference to the accompanying drawings, the four figures of which indicate four steps in the manufacture of a spindle according to the invention.

Figure 1 is an illustration of the shape of the flat strip from which the spindle is made;

Figure 2 illustrates the next stage of manufacture in which the edges of the strip are turned up;

Figure 3 illustrates the strip rolled into cylindrical form;

Figure 4 illustrates the completed spindle.

A long strip of suitable material, of a width equal to the length of the spindle when finished, is fed into a press adapted to divide the long strip up into a number of transverse strips such as that marked 5 in Fig. 1. At the same time the press punches out a longitudinal slot 6 in the centre of each strip 5, and it also removes the material at the four corners, leaving the blanks 7, 7 and the extending edges 8, 8 therebetween.

These strips 5 are then passed into another machine, which bends off the edges 8, 8 at 100

right-angles to the main body of the strip forming a shallow channel-shaped member (Fig. 2). Due to the removal of the corners of the strip the bent-off edges do not extend to the ends of the strip, and only the interior portion of the strip (as regards its length) is a hollow channel.

Obviously the two operations thus far described may in practice be effected in a single automatic machine instead of in two separate machines.

The chain lines 9 (Fig. 1) represent the edges proper of the flat portion of the strip, but the bent-off edges 8, 8 are bent slightly about the lines 9 but mainly about the chain lines 10, 10 which are inset slightly with respect to the lines 9, 9 and do not extend axially as far as the blanks 7, 7. When this has been done the bent-off edges (Fig. 2) are inset slightly, over the main portion of their length, with respect to the edges of the flat part of the strip marked 11, 11.

In the next operation the flat part of the strip is bent or rolled up, in one or more steps, to form a hollow cylinder. In this operation the opposite edges 11, 11 are brought into contact, but, on release from the rolling machine, the natural resiliency of the material causes the opposite edges of the spindle to spring out slightly, as indicated by Fig. 3 where the edges 11, 11 are seen not to be in contact. A longitudinal internal slot 12 is formed between the bent-off edges 8, 8.

In the final operation the spindle is set, the ends 13 being pressed outwardly as indicated in Fig. 4. This serves to draw up the opposite edges 11, 11 into contact, and the slot 12 between the bent-off edges 8, 8 is then truly an internal slot, which does not extend up to the ends of the spindle.

The end discs (not shown) of the spool may be secured at the ends of the spindle by a pressing operation or by welding. The present invention is not concerned with the manner in which the end discs are fixed on the spindle.

It should be noted that the bent-off edges 8, 8 are parallel to one another when the spindle is formed (Fig. 4) and that they are pointing towards slot 6. In this case slots 12 and 6 are diametrically opposite one another, and slot 12 is the longer. It will be evident that the end of the paper or like roll which is to be wound upon the spindle will be first inserted into slot 12, and that the slightly rounded external edges of this slot act as a lead or guide for the end of the roll into this slot, and that the parallel sides of the slot act to guide the end of the roll through the spindle and into slot 6.

Furthermore, it will be seen from Figs. 2 and 3 that the length of the bent-off edges 8, 8 is greater than the length of the internal slot 12. By suitably determining the amount of

the cut-off corners 7, 7, 7 the adjacent ends of the edges 8, 8 can be arranged to form a bottom stop or rest for the camera key when it enters the co-operating slot in the end disc at that end of the spindle.

What we claim as our invention and desire to secure by Letters Patent is:—

1. A metallic spindle for the spool of a camera film or the like, formed from a flat rectangular strip into a hollow cylinder with the adjacent edges of the strip inturned to form an internal longitudinal slot, characterized in that the inturned edges extend axially beyond the slot, but not up to the ends of the spindle.

2. A metallic spool spindle for photographic film spools comprising a tube formed of sheet metal rolled upon itself to provide a split tube, the longitudinal edges of said sheet metal being cut-away at the corners thereof, and the portions of said longitudinal edges intermediate of said cut-away portions being inset in parallel lines to form widened side walls of a normally open paper strip receiving slot, said sheet metal being also formed with a slot substantially parallel to the first slot located in an opposite side of said split tube.

3. A spindle for photographic film spools comprising a blank of sheet metal rolled upon itself to provide a split tube, the longitudinal edges of said blank being cut-away at their corners and formed with inwardly projecting reinforcing flanges spaced apart to provide a normally opened strip receiving slot, the cut-away corner portions of said split tube outwardly of said flanges forming abutting edges to prevent the closing of said slot, the ends of said tabular spindle being connectible to spool discs.
